UNITED STATES PATENT OFFICE.

ARTEMUS M. YARBROUGH, OF HOPE, ARKANSAS.

HATRACK.

Application filed January 21, 1926. Serial No. 82,697.

The invention relates to hatracks particularly adapted for use by automobilists and has for its object to provide an annular hat receiving member which member is provided 5 with an arm hingedly connected to the side of an automobile bow, and with a second arm, to which is connected a coiled spring which in turn is connected to a member carried by the adjacent bow of the top, said 10 coiled spring forms means whereby the brim of the hat will be maintained adjacent the top of the automobile and at the same time allows the annular member to be moved downwardly for removing or replacing the 15 hat.

A further object is to form the device from two pieces of wire having segmentally shaped portions terminating in portions twisted together, and which twisted portions 20 terminate in oppositely extending arms pivotally mounted in apertures of a bracket carried by the bow. The other ends of the segmentally shaped members terminate in radially disposed engaging arms which are 25 clamped together, and one of which arms extends beyond the other, and terminates in an eye for the reception of one end of the spring.

With the above and other objects in view 30 the invention resides in the combination and arrangement of parts as hereinafter set forth, shown in the drawing, described and claimed, it being understood that changes in the 35 precise embodiment of the invention may be made within the scope of what is claimed without departing from the spirit of the invention.

In the drawing:—

Figure 1 is a side elevation of the hat- 40 rack showing the same applied to adjacent ribs of an automobile top.

Figure 2 is a top plan view.

Figure 3 is a detail perspective view of 45 the plate and a portion of the twisted wire arm carried by the hat receiving member.

Referring to the drawing, the numerals 1 and 2 designate adjacent horizontal portions of an automobile top bow, and 3 the annular hat receiving member. The annular 50 hat receiving member is formed from covered segmentally shaped sections 4, formed of wire, and is adapted to receive therein

a crown 5 of a hat. The segmentally shaped members 4 are normally in a horizontally disposed position as shown in Figure 1, and the brim 6 of the hat engages the upper side thereof, for supporting the hat within the annular member and adjacent the inner side of the top of the automobile. Segmentally shaped members 4 terminate in an arm 7 55 radially disposed in relation to the annular member and formed by twisting the wires together, and which wires, after being twisted, terminate in oppositely extending arms 8, which are disposed in apertured ears 9 of a bracket 10 secured to the bow 1. The other ends of the segmentally shaped members 4 60 terminate in arms 11 and 12 which engage each other, and which are securely clamped together by means of a clamp 13. Arm 12 is 65 longer than the arm 11 and terminates in an eye 14, to which is connected a coiled spring 15, which is provided with an eye 16, which is received by the hook 17 carried by the bow 2. The coiled spring 15 forms means 70 for maintaining the hat carrying member in a horizontal position, the parts against rattling, and at the same time allows the hat carrying annular member to be pulled 75 downwardly on its hinging point 8 to a position where the hat may be placed in position or removed. If desired the eye 16 may be removed from the hook 17 during the manipulation of the device if desired.

From the above it will be seen that an 80 automobile hatrack is provided for automobile tops, which is simple in construction, the parts reduced to a minimum, and one which may be cheaply manufactured and sold as the main parts of the body are 85 formed from wire. It will also be seen that the hatrack will positively support a hat in a position where it will not be damaged, and where it can be readily reached when desired.

The invention having been set forth what is claimed as new and useful is:—

A hat rack comprising an annular hat crown receiving member, said crown receiving member being formed from oppositely disposed segmentally shaped members, one pair of ends of the segmentally shaped members terminating in a portion twisted together thereby forming a radially disposed arm, the 100

ends of the members forming the radially disposed arm terminating in oppositely extending arms, said arms being pivotally mounted in apertures of a bracket, the other ends of the segmentally shaped members terminating in engaging radially disposed arms, one of said last named arms being

longer than the other, means for clamping said arms together, the long arm terminating in an eye and an anchored coiled spring connected to said eye. 10

In testimony whereof I hereunto affix my signature.

ARTEMUS M. YARBROUGH.
